Specification for Design.

Patented Feb. 8, 1921.

Application filed June 7, 1920. Serial No. 387,187. Term of patent 7 years.

To all whom it may concern:

Be it known that we, FRITHJOF H. ELIASON and WILLIAM F. SCHWAHL, citizens of the United States, residing at Newark, county of Essex, and State of New Jersey, have invented a new, original, and ornamental Design for Intensifiers for Spark-Plugs, of which the following is a specification, reference being had to the accompanying drawing, forming part thereof.

Figure 1 is a top view of the new and ornamental intensifier for spark plugs.

Fig. 2 is a side view of the intensifier, and

Fig. 3 is a bottom view of the intensifier.

We claim:

The ornamental design for an intensifier for spark plugs, as shown.

FRITHJOF H. ELIASON.
WILLIAM F. SCHWAHL.
